UNITED STATES PATENT OFFICE.

ROLAND C. PINDER, OF LIMA, OHIO, ASSIGNOR TO P. & F. MANUFACTURING COMPANY, OF MINSTER, OHIO, A FIRM COMPOSED OF GEORGE H. KNOSTMAN AND ALFRED B. FISCHER.

TONE-MODULATING DEVICE FOR PIANOS.

1,389,160.

Specification of Letters Patent. Patented Aug. 30, 1921.

Application filed September 8, 1920. Serial No. 408,811.

To all whom it may concern:

Be it known that I, ROLAND C. PINDER, a citizen of the United States, residing at Lima, in the county of Allen and State of Ohio, have invented certain new and useful Improvements in Tone-Modulating Devices for Pianos, of which the following is a specification.

This invention relates to pianos and the primary object of the invention is to provide an improved attachment for pianos which is so constructed that a novel tone will be given to the piano which will be similar to a string instrument, such as a ukulele, mandolin or the like.

Another object of the invention is to provide an improved attachment for pianos embodying a movable member adapted to be brought into and out of position between the strings and the piano hammers, the attachment when placed between the strings and the hammers being adapted to give a metallic tone to the piano similar to a string instrument.

A further object of the invention is to provide an improved means for raising and lowering the attachment into and out of operative position in relation to the piano hammers and strings and an improved means for holding the attachment in its adjusted positions.

A further object of the invention is to provide an improved means for connecting the flexible tabs for the strings to the attaching bar so that the tabs can be readily adjusted and held in alignment with the strings.

A further object of the invention is to provide a novel striker for the strings carried by the flexible strips, so that the strikers will not become entangled with the strings, and to give a pleasing string instrument tone to the piano.

A still further object of the invention is to provide an improved attachment for pianos for giving a stringed instrument tone thereto, which will be durable and efficient in use, one that will be simple and easy to manufacture, and one which can be placed upon the market and incorporated with a piano at a minimum cost.

With these and other objects in view, the invention consists in the novel construction, arrangement and formation of parts, as will

be hereinafter more specifically described, claimed and illustrated in the accompanying drawings, forming a part of this specification, in which drawings:

Figure 1 is a fragmentary transverse section through a player piano showing the improved attachment connected thereto and in operative relation to the piano hammers, the attachment also being shown in its inoperative position in dotted lines.

Fig. 2 is a fragmentary detail perspective view of the player piano spool box showing the control device for the attachment operatively connected thereto.

Fig. 3 is a front elevation of the string engaging portion of the improved player piano attachment.

Fig. 4 is an enlarged fragmentary detail cross sectional view through the string engaging portion of a piano attachment.

Fig. 5 is an enlarged fragmentary detail view of one of the string engaging sections.

Fig. 6 is a fragmentary horizontal section through the control for the device.

Fig. 7 is an enlarged fragmentary elevation of one of the guides utilized for the cable of the control for the attachment.

Referring to the drawings in detail, wherein similar reference characters designate corresponding parts throughout the several views, the letter A indicates a piano, and B, the improved ukulele attachment therefor. The piano A may be of any preferred type or make, either of the player or non-player type. As shown the piano A is of the player type and includes the casing 10, the spool box 11, the sound board 12, the strings 13, and the piano hammers 14. The casing 10 of the piano may be of the usual shape or configuration and includes the side walls 15.

The improved ukulele attachment B comprises the string engaging portion C and the control portion D. The string engaging portion C includes the longitudinally extending rail 16 which can be made in any desired length and cut to fit the piano with which it is to be associated. The rail 16 has secured to its terminals in any preferred manner, the forwardly extending arms 17, and these arms are in turn hingedly or pivotally connected at their free terminals to the side walls 15 of the piano case.

10 by means of screws or the like 18. The rail 16 supports the key-engaging sections 19, each one of which is adapted to engage one octave of the piano. There may be as 5 many of the sections 19 as there are octaves of the piano and as shown there are eight of the sections 19 for the treble end of the piano, and a felt muffler pad 20 for the bass end of the piano. The felt muffler pad 20 10 is secured directly to the rail in any preferred manner either by glue or by suitable retaining screws or the like and is of preferably one continuous sheet. The sections 19 are each divided into eight de- 15 pending flexible fingers 21 and the terminals of these fingers carry the metallic strikers 22. The sections are preferably formed of relatively stiff fabric and are slotted to form the fingers 21. The upper 20 terminals of the sections 19 are secured by suitable adhesives or the like 23 to the inner surface of attaching strips 24 adjacent to their upper edges. The inner surfaces of these attaching strips 24 adjacent to their 25 lower edges have grit, sand or the like 25 applied thereto for frictionally engaging the fingers 21 so as to hold the same in direct alinement with the strings 13 of the piano and to prevent relative lateral move- 30 ment thereof. In applying the device in place, the rail 16 is cut to properly fit the inside of the case, and the brackets or arms 17 are secured thereto and then connected to the case 10 by means of the screws 18. 35 The rail is so positioned that the same is placed about one quarter of an inch away from the strings. The muffler strip 20 is then placed in position on the rail 16 for the bass strings. The sections 19 are then 40 placed in position starting from the bass strings. The sections are so placed that each of the fingers 21 will be in direct alinement with the piano strings, and if by any reason any one of the fingers will not lie 45 in direct alinement to the strings, it is merely necessary to move the same slightly over to aline therewith, and when the strips 24 are placed in position, the abrasive 25 will hold the fingers in their adjusted positions and 50 absolutely preclude displacement thereof. The strips are held in position by suitable screws 27 or the like. Each section 19 is placed in position similar to the sections just described. It can be seen that each of 55 the strips 24 is provided with openings 28 for the screws 27 or other fastening elements. To limit the downward movement of the rail 16 in relation to the strings 13, stops 29 are secured to the side walls 15 60 of the case 10 in the path of the arms 17. The improved control D includes a vertical sliding rod 30, the upper end of which has secured thereto in any preferred manner the flexible cable 31 for raising and lowering the rail 16. A pair of spaced guides 32 is secured to the spool box 11 of the player piano and each one of these guides includes a body 33 provided with a bore 34 in which is fitted a felt bushing or the like 35. The body 33 is provided with a vertical slit 36 70 which extends inwardly from one side edge thereof to the bore 34. The sliding rod 30 is fitted in the felt bushings 35 and is adapted for sliding movement therein, but the felt bushings form frictional locks therefor 75 and effectively hold the same in its raised or lowered position. Each of the guides 32 is held in position by means of fastening screws 37 and 38 which extend through the body 33 and into a spool box 11. The screw 38 80 extends through the slit portion 36 of the guide and it can be seen that by tightening the screw 38 the pressure of the guides on the rod 30 can be readily controlled. The lower end of the rod 30 is angled as at 40 85 and provided with a right angularly extending handle 41. A guide strap 42 is secured to the front face of the spool box 11 and forms a positive guide for the rod 30 and precludes lateral movement thereof. 90 Blocks 43 are secured to the upper surface of the spool box 11 and these blocks 43 carry outwardly extending guide pins or rollers 44. These guide pins or rollers 44 may be provided with the usual sound absorbing washers 45 if so desired. As clearly shown in Fig. 1 of the drawings, the flexible cable 31 is trained under the first guide roller 44 and then over the second guide roller 44 and is secured to the upper edge of the rail 16 100 adjacent to the central portion thereof. It can be seen that when the rod 30 is raised, the rail 16 will be swung on the pivots 18, thus moving the flexible fingers 21 from out of the path of the hammers 17, 105 thus allowing the piano to be used in the ordinary manner. When it is desired to use the attachment, however, the rod 30 is lowered in the bearings which will cause a slack in the cable 31 and thus permit the rail 16 110 to swing on the pivots 18 and position the flexible fingers 21 in the path of the hammers. 115 The metallic strikers 22 may be of any preferred configuration and secured to the lower terminals of the fingers in any preferred manner. As shown these strikers are bent entirely around the lower edge of the fingers and secured thereto by suitable bent tongues or the like. 120 It can be seen that when a piano hammer strikes one of the flexible fingers 21, the strikers 22 will be vibrated back and forth and will give a metallic note to the strings, thus giving the tone of a ukulele or a mando- 125 lin to the piano. 130 From the foregoing description it can be seen that an improved attachment has been provided for pianos for changing the tone thereof which can be quickly and easily

secured thereto by the ordinary layman and not require the services of a skilled mechanic to apply the same thereto.

Changes in details may be made without departing from the spirit or scope of this invention; but,

I claim:

1. The combination with a piano including strings and hammers, of an attachment 10 for the piano including a rail, arms carried by the rail, means pivotally securing the free terminals of the arms to the piano, a plurality of flexible finger strips secured to the rail and arranged between the strings and 15 hammers, a vertically disposed sliding operating rod, friction guides for said rod to hold the same in adjusted position, and a flexible cable connected to the upper end of said rod and to the rail whereby upon movement of the rod, the rail will be raised or 20 lowered.
2. The combination with a piano including strings and hammers, of an attachment 25 for the piano including a longitudinally extending rail, means pivotally connecting the rail to the piano, a plurality of flexible finger strips secured to the rail, metallic strikers carried by the fingers arranged to engage the strings, an adjusting rod, a pair 30 of spaced vertically disposed guides for the rod, felt bushings carried by said guides and arranged to frictionally engage the adjusting rod to hold the same in an adjusted position, guide rollers carried by the piano and 35 a flexible cable connecting the upper end of the rod with the rail and trained around said guide rollers whereby upon movement of the rod the rail will be raised or lowered.
3. The combination with a player piano 40 including a plurality of strings, a plurality of hammers, and a spool box, of an attachment for the piano including a movable rail,

a plurality of flexible finger sections secured to the rail, a plurality of strikers carried by the flexible fingers adapted to engage the 45 strings and a pair of guides secured to the spool box, each of the guides having a bore, a felt bushing fitted in said bore arranged to form a friction grip, a vertically disposed rod fitted in said bushings, the guides being 50 split, means for adjusting the split portions of the guides toward and away from each other, a flexible cable connecting the upper end of the rod with the rail, and an operating handle formed on said rod. 55

4. The combination with a player piano including a plurality of strings, a plurality of hammers, and a spool box, of an attachment 60 for the piano including a movable rail, a plurality of depending flexible fingers carried by the rail, metallic strikers carried by the free terminals of the fingers, a vertically disposed sliding rod, a pair of spaced friction guides, carried by the spool box arranged to receive said rod, a flexible cable 65 connecting the upper end of said rod with the rail, a right angular bent terminal formed on said rod at the lower end thereof arranged to extend in front of said spool box, and a guide strap for said right angular 70 bent end.

5. The combination with a piano including strings and hammers, of an attachment 75 therefor including a rail, an attaching strip, a flexible finger strip secured at its upper end to the attaching strip, means for securing the attaching strip to the rail to clamp the finger strip between the attaching strip and the rail, friction members carried by the inner surface of the attaching strip arranged 80 to engage the finger strip to hold the lower edge of the same in an adjusted position.

ROLAND C. PINDER.
